PACKAGING MACHINE

Ralph N. Doble, Hingham, Mass.

Original application October 19, 1937, Serial No. 169,763. Divided and this application December 29, 1938, Serial No. 248,297

4 Claims. (Cl. 93—3)

This invention relates to the manufacture of tea bags, coffee bags and the like, and particularly to the manufacture of bags of the so-called "pouch" type.

5 A common method of making a tea bag or coffee bag of the pouch type is to place a blank of bag material, usually a gauze fabric, on a supporting plate which has a bag-forming opening therein with the opening centrally situated beneath the blank, and then to force the blank through the opening by means of a combined bag-forming and filling tube with the result that 10 the bag material becomes folded up around the filling tube by the edges of the bag-forming opening. While the filling tube still remains within the partially formed bag, a charge of tea, coffee or other ingredient is delivered into the tube and thus into the bag after which the tube is withdrawn, the marginal portions of the 15 blank are gathered together to close the mouth of the bag and a tie string or other fastening device is then secured to the closed mouth of the bag.

The blank which is commonly used is a square blank, and when the blank is being forced through the bag-forming opening of the supporting plate by means of the bag-forming and filling tube the central portion of each side of the blank as well as the corner portions of the 20 blank are folded up against the tube in an indeterminate manner. Because the radial distance from the center of the blank to the center of each side is less than the radial distance from the center of the blank to each corner, said 25 corners of the blank will extend above the center portion of the side edge of the blank when the blank has been formed into the bag shape by being forced through the bag-forming opening, and in order to make a tight bag it has been 30 customary to apply the fastening device to the mouth of the bag at a point in which the entire edge of the blank will be above the fastening device. In other words, the fastening device is usually applied to the mouth of the bag at a point 35 below the location of the center portion of the side edges of the blank when they have been gathered together to form the bag. After the bag has been tied or the mouth of the bag has 40 been fastened then the projecting corners are usually trimmed off a short distance above the fastening device. Where a bag is made in this way, it is necessary to use a blank which is large enough so that when the tie string or fastening device is placed around the mouth of the bag 45 below all the edges of the blank, the bag will

still have sufficient capacity to hold the desired amount of tea or coffee.

One of the objects of the present invention is to provide a novel bag-forming means by which a tight bag can be made even when the tie 5 string is placed above a portion of the edges of the folded blank, thereby making it possible to form a bag having a given capacity from a blank of smaller dimensions than would be required to make a bag of the same capacity if the tie 10 string were placed below all the edges of the bag material.

In accordance with my present invention, I use a supporting plate which is specially constructed so that as the blank of bag material is 15 forced therethrough by the bag-forming and filling tube, the central portion of each side of the blank will be formed into an inner fold which is overlapped and enclosed by another or outer fold formed from corner portion of the blank. 20

When the bag is completed by gathering the mouth thereof together and applying the fastening device or tie string, a tight bag will be produced even if the tie string is placed above the 25 edge of the inner folds but below the edge of the outer folds, since the inner folds are held closed by the outer folds which are tightly clamped thereabout.

In order to give an understanding of the invention I have illustrated in the drawings a selected embodiment thereof which will now be described after which the novel features will be pointed out in the appended claims. 30

In the drawings:

Fig. 1 is a fragmentary plan view of a portion 35 of a bag-forming machine embodying my invention and illustrating the special supporting plate employed to produce the above described results;

Fig. 2 is an enlarged plan view of the supporting plate;

Fig. 3 is a vertical fragmentary sectional view illustrating the operation of the combined bag-forming and filling tube in making the bag;

Fig. 4 is a somewhat diagrammatic view showing 45 the partially formed bag in plan view and illustrating the relation of the inner and outer folds;

Fig. 5 is a side view of the partially formed bag illustrating the manner in which the bag 50 material is folded as it is forced through the bag-forming opening;

Fig. 6 is a view of the completed bag.

Inasmuch as the present invention relates to the supporting plate and its bag-forming open- 55

ing and the manner in which the blank of bag material is formed by said plate, I have not thought it necessary to illustrate herein a complete machine but have only shown such portions of a bag-forming machine as may be necessary to give a proper understanding of the invention. In Fig. 1, 1 indicates the supporting plate which has a bag-forming opening 2 therein. The bag material 3 is shown as being in the form of a strip or web which is taken from a supply roll 4 and is fed to the supporting plate 1 through the medium of feed rolls 5, 6. After a suitable length of the bag material has been fed over the supporting plate 1 then such length is cut off from the strip 3 by means of a suitable shear device 7, and the portion which is thus cut off then constitutes a blank of bag material from which a bag is formed. This blank is usually square and is illustrated by the dotted lines 8 in Figs. 2 and 3. After the blank 8 has been placed in position over the bag-forming opening 2 said blank is formed into a bag by means of a bag-forming and filling tube 9 which is forced downwardly against the blank 8 and through the opening 2, thereby causing the outer portions of the blank of bag material to be folded up around the tube by the edges of the bag-forming opening 2.

During the downward movement of the tube 9 the bag material is not only forced through the opening 2 but also forced into or through the opening 10 between two jaw members 11, 12 that are mounted on a suitable turret 13, as shown in Fig. 3.

When the bag has been thus formed, a charge of tea, coffee or other ingredient is deposited in the tube 9 and thus into the bag, and the tube is then withdrawn, after which the jaws 10 and 11 are closed together to close the mouth of the bag and a tie string or fastening device 14 is then applied to the bag to hold the mouth closed. The upwardly projecting corners of the bag material are then trimmed off thereby to produce a bag 41 as shown in Fig. 6.

The parts thus far described with the exception of the supporting plate 1 are or may be of the same construction as illustrated in Patents No. 1,700,672, January 29, 1929; No. 1,857,662, May 10, 1932, and No. 1,911,805, May 30, 1933.

According to my present invention I employ a supporting plate having a bag-forming opening of special construction which is designed to fold the bag material around the tube 9 in a special way so that a tight bag will be formed even if the tie string or fastening device is placed above the edge of the center portion of each side of the blank. This makes it possible to use a smaller blank for a bag of a predetermined capacity than could be used if the tie string were placed entirely below the entire edge of a folded blank.

The bag-forming opening in the plate 1 has the central open portion 2 and four curved slots 15 extending outwardly therefrom, said slots forming between them fold-forming portions 16. The plate is formed on its underside with an inclined finger 17 extending downwardly from each fold-forming portion 16, each finger having a sort of tangential arrangement with respect to the central portion of the opening, and inclining in a direction opposite to that of the adjacent slot 15.

The square blank 8 of bag material is fed onto the supporting plate in the position shown in dotted lines 2 with the fold-forming portion 16 opposite the central portions 18 of the sides of

the blank. As the bag-forming tube 9 is entered into the bag-forming opening 2 the portions 19 of the blank 8 forming the central portion of each side thereof are each formed into a fold 20 around one of the fold-forming portions 16, and each corner portion 21 of the blank is formed by the edge 22 into a fold 23 which is oppositely disposed from the adjacent folds 20, and which is also located on the outside of one of the folds 20. The folds 20 into which the portions 19 of the blank are formed may be termed "inner folds," and the folds 23 formed from the corners of the blank by the edges 22 and the slots 15 and which are located outside of the folds 20 may be termed "outer folds." In forming these inner and outer folds 20 and 23, the outer side of each inner fold 20, which is indicated at 39 in Fig. 4, constitutes the inner side of an adjacent outer fold, this portion 39 being common to both folds. The relative position of each slot 15 and the adjacent folding portion 16 and finger 17 causes the inner folds 20 to hug the tube 9 and causes the outer folds 23 to overlap the inner folds as best seen in Figs. 4 and 5. The overlapping fold formation which is thus initiated by the fold-forming portions 16 and fingers 17 is maintained by the jaws 11, 12 as the bag is forced through said jaws by the tube 9, and when the charge of tea, coffee or other ingredient has been deposited in the bag and the tube 9 has been withdrawn, this overlapping relation of the folds 20 and 23 is still maintained when the jaws 11 and 12 are closed together to close the mouth of the bag.

The inner folds 20, which are formed from the side portions 8 of the blank, are shorter than the outer folds 23 which are formed from the corner portions of the blank, since the radial dimension of the blank midway of each side is shorter than the radial dimension of the blank at the corners. With this arrangement, the ends 24 of the shorter inner folds 20 are, therefore, nearer the bottom of the bag than the ends 34 of the longer outer folds 23. In the formation of these folds 20 and 23, the shorter inner folds are laid or placed behind the longer outer folds so that the ends 24 of the shorter inner folds will be covered by an overlapping outer fold.

After the bag has been formed and filled and the mouth has been closed by the jaws 11 and 12, then the tie string or fastening device 14 is applied to the closed mouth of the bag, and I propose to apply such fastening device to the bag mouth above the ends 24 of the shorter inner folds 20, as indicated by the dot and dash line 25 in Fig. 5. Although the fastening device 14 is placed on the bag above the ends 24 of the inner folds 20, yet since these inner folds are tucked within the outer folds 23 and are closely held in their tucked-in relation by the tightening of the fastening 14, there is no possibility that the contents of the bag may leak out over the edges 24 of the shorter inner folds 20.

By having the tie string or fastening device placed above the ends 24 of the inner folds 20, it is possible to make a bag having a given capacity from a smaller piece of bag material than if the tie string were placed below said ends 24. This means that for making bags of a certain size it is possible by means of my invention to use a web 3 of bag material which is narrower than that formerly used and to use a shorter length of such web 3 for forming each bag.

In the bag 41 the corner portions only of the blank are located above the tie string and fastening device, and the central portions 18 of the

de edges of the blank are located below the tie tring or fastening device, but because such portions 18 are formed into inner folds 20 which re tucked within or overlapped by the longer outer folds 23 formed from the corner portions of the blank there is no possibility that the contents of the bag will leak out over the edges 24 of the shorter inner folds.

In Fig. 5 the dotted line 26 indicates the line along which the corners of the bag may be rimmed off after the fastening device has been secured thereto.

In order to assist in making the folds 20, 23, may, if desired, employ additional folding plates 1, 28 beneath the supporting plate 6, said additional plates 21, 28 being carried by the fingers 1 and having slots 29 corresponding to the slots 5. These additional plates 21, 28 serve to hold the folds 20 and 23 in their overlapping relation as the bag material is carried through the plates and into and between the jaws 11 and 12.

The bottom of the tube 9 is shown as having a stepped or toothed surface presenting a plurality of teeth 30. The purpose of these teeth is to prevent the bag material from twisting out of its proper position during the initial movement of the tube 9 into and through the opening 2.

This application is a division of my application Serial No. 169,763, filed October 19, 1937, which has matured into Patent No. 2,118,551.

I claim:

1. A bag-forming machine comprising a plate having a bag-forming opening therein presenting a central portion and a plurality of curved slots extending outwardly therefrom at an inclination to a radial line, said curved slots having between them fold-forming portions, and a bag-forming tube adapted to be inserted through the central portion of the opening, thereby to force a blank of bag material through the opening, said fold-forming portions forming inner folds in the bag material as it passes through said opening and said slots forming outer folds which overlap the inner folds.

2. A bag-forming machine comprising a plate having a bag-forming opening presenting a central portion and a plurality of curved slots extending outwardly from the central portion at an inclination to a radial line, said slots being

all inclined in the same direction and having between them fold-forming portions, and a bag-forming tube adapted to be inserted through the central portion of the opening, thereby to force a blank of bag material through said opening, said fold-forming portions forming inner folds in the bag material which extend circumferentially of the bag in the same direction and said slots forming outer folds which overlap the inner folds and extend circumferentially of the bag in the opposite direction.

3. A bag forming machine comprising a plate having a bag-forming opening presenting a central portion and a plurality of curved slots extending outwardly from the central portion at an inclination to a radial line and having between them fold-forming portions, fold-retaining fingers depending from the fold-forming portions, and a bag-forming tube adapted to be inserted through the central portion of the opening, thereby forcing a blank of bag material through said opening, said fold-forming portions and fold-retaining fingers forming in the bag material inner folds extending in one direction circumferentially of the bag, and said slots forming in the bag material outer folds which overlap the inner folds and extend in the opposite direction circumferentially of the bag.

4. A bag-forming machine comprising a plate having a bag-forming opening presenting a central portion and a plurality of curved slots extending outwardly from the central portion at an inclination to a radial line, said slots being all inclined in the same direction and having between them fold-forming portions, fold-retaining fingers depending from the fold-forming portions and each having a downward inclination in a direction opposite to that of the adjacent slot, and a bag-forming tube adapted to be inserted through the central portion of the opening, thereby forcing a blank of bag material through said opening, said fold forming portions and fold-retaining fingers forming in the bag material inner folds extending in one direction circumferentially of the bag and said curved slots forming in the bag material outer folds which overlap the inner folds and extending in the opposite direction circumferentially of said bag.

RALPH N. DOBLE. 50
